United States Patent

Des. 240,414
Patented July 6, 1976

240,414

ADJUSTABLE WHEELCHAIR

Morton I. Thomas, Monroe, N.Y., assignor to
Temco Products, Inc.

Filed Sept. 23, 1974, Ser. No. 508,066

Term of patent 14 years

Int. Cl. D12—12

U.S. Cl. D12—131

FIG. 4

FIG. 3

FIG. 1 is a right front perspective view of an adjustable wheelchair showing my new design;

FIG. 2 is a left front perspective view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for an adjustable wheelchair, substantially as shown.
